UNITED STATES PATENT OFFICE.

TONY MIECZEJESKI, OF ROSEMONT, WEST VIRGINIA.

MULTIPLE AND FOLDABLE BED.

1,357,578.

Specification of Letters Patent. Patented Nov. 2, 1920.

Application filed July 15, 1920. Serial No. 396,549.

To all whom it may concern:

Be it known that I, TONY MIECZEJESKI, a citizen of Poland, residing at Rosemont, in the county of Taylor and State of West Virginia, have invented certain new and useful Improvements in Multiple and Foldable Beds, of which the following is a specification.

This invention relates to certain new and useful improvements in multiple and foldable beds and is particularly designed to provide a simple construction wherein the head and foot members of an ordinary bed are utilized with supplementary head and foot members for providing a series of connected beds, the structure being such as to enable the same to be readily folded into compact form when not in use or during shipment.

The objects above outlined are preferably obtained by means of the form, combination and arrangement of parts hereinafter more fully described, shown in the accompanying drawing, and claimed.

In the drawings, wherein like reference characters indicate similar parts throughout the several views,

Figure 1 is a side elevational view, partly broken away, of a single bed constructed in accordance with the present invention,

Fig. 2 is an end elevational view thereof,

Fig. 3 is a fragmentary top plan view of one end of the same,

Fig. 4 is a view similar to Fig. 1 with parts broken away and supplemental rails, head member and foot member attached for providing a multiple bed,

Fig. 5 is a top plan view of one of the head or foot members folded,

Fig. 6 is a sectional detail view on a larger scale and taken substantially upon line VI-VI of Fig. 2,

Fig. 7 is a horizontal sectional view taken substantially upon line VII-VII of Fig. 6, and

Fig. 8 is an enlarged perspective view of one of the triangular brace members forming part of the means for maintaining the head and foot members in expanded operative condition.

Referring more in detail to the several views, the present invention embodies head and foot members 5 which are of similar construction and which each comprise two hingedly connected vertical sections, the hinge 6 thereof being substantially centrally of the same as seen in Fig. 2, and in this figure,

it will be noted that the pivot of the hinges preferably resides in a long rod 7 extending from the top rail 8 to the bottom rail 9. The legs 10 of the head and foot members 60 may be formed in continuation of the top rail 8 or in any desired or well known manner, and these legs are provided with headed studs 11 of the usual and ordinary form constituting part of the corner fastenings of 65 the bed and adapted for reception in the end sockets of the side rails 12, one of which sockets is shown at 13 in Fig. 1.

As shown in Fig. 4, the head and foot sections or members 5 together with the rails 70 12 will form one complete bed frame and the studs 11 at the outer sides of the members 5 may be connected with additional side rails 12' and supplemental foot members 5' so as to form a multiple bed, or in other 75 words, three beds with only four head and foot members, each bed being of rigid and durable construction and the end beds utilizing the head and foot members of the intermediate beds. Obviously, this addition of 80 supplemental side rails and head and foot members may be indefinitely continued for providing any required number of beds.

Means are provided for retaining the head and foot members in their expanded 85 operative condition and such means includes tapered dove-tail lugs 14 rigid with and depending from each section of the head and foot members adjacent to and at opposite sides of the lower hinge 6, as seen in Fig. 90 2, said lugs 14 being adapted for reception within similarly shaped grooves 15 provided in the base of a triangular member 16 which is best shown in Figs. 2 and 6 to 8. The member 16 is provided with a transverse aperture 17 adjacent its apex adapted for reception of the end of a securing rod 18 as will presently become apparent. The triangular member of the head section has its lugs and grooves tapered reversely to 100 that of the foot section so that when the members 16 of both the head and foot sections are slid onto the lugs 14, the same are limited in movement toward each other whereupon the rod 18 is projected through 105 the apertures 17 of both members 16 and thus the sections of the head and foot members are effectively braced and prevented from folding.

If it is desired to collapse the bed, it is 110 merely necessary to remove the nuts 19 and remove the rod 18 after which the members

16 may be slid outwardly for detachment from the lugs 14. The side rails 12 may then be removed in the usual way and the head and foot members are then free to be 5 folded to the condition shown in Fig. 5.

From the foregoing description, it is believed that the construction and operation as well as the advantages of the present invention will be understood and appreciated by those skilled in the art.

10 Minor changes may be made without departing from the spirit and scope of the invention as claimed.

What is claimed as new is:

- 15 1. In a foldable bed, head and foot members comprising similar vertical sections hingedly connected together, a pair of tapered dove-tailed lugs depending from the bottom rail of each of said head and foot members and at opposite sides of the hinge connection between the sections of said head and foot members, triangular members having tapered dove-tailed grooves in the bases
- 20

thereof for reception of said tapered dove-tailed lugs, said triangular members being 25 provided with transverse openings adjacent the bases thereof, and a tie rod extending between said triangular members and having screw threaded ends projecting through the openings of the latter, and nuts threaded 30 upon the ends of said rod outwardly of said triangular members for maintaining the sections of the head and foot members in expanded condition.

2. In a foldable bed, head and foot members, detachable side rails, said head and foot members each being composed of vertical sections hinged together, and means including a longitudinally disposed rod extending beneath the side rails and connecting 40 said head and foot members for maintaining the sections of the latter in open or expanded condition.

In testimony whereof I affix my signature.

TONY MIECZEJESKI.
